UNITED STATES PATENT OFFICE

RICHARD M. BINSWANGER, OF EAST ORANGE, NEW JERSEY, ASSIGNOR TO KOPS BROS. INC., OF NEW YORK, N. Y., A CORPORATION OF NEW YORK

APPAREL GARMENT

Application filed January 26, 1928. Serial No. 249,589.

This invention relates to an apparel garment and particularly to that type of under-garment known as a girdle and adapted to be secured on the body of the wearer by connecting the portions of the garment to one another at one side thereof. The object of the invention in the present case is to include in a garment of this type a suitable abdominal supporter, the position of which may be varied depending upon the length of the abdomen of the wearer. The garment is preferably so constructed that the parts thereof are connected at the side of the body so that there is included a front member, a back member, and elastic side members, by which latter the necessary circumferential tension is provided to cause the garment to adequately adjust and maintain itself in position when in use. The feature of the abdominal supporter to which my present invention more particularly relates is one in which this supporter is connected in such a manner as to be adjustable to position in its entirety and to be secured in place in the garment within reasonable limits so that it may be raised and lowered, that is, placed in different positions depending upon the length of the abdomen of the wearer. This feature together with the construction of the abdominal support member will be hereinafter more particularly described.

In the drawing Figure 1 is a perspective view illustrating the use of the garment made in accordance with this invention.

Fig. 2 is a perspective view on an enlarged scale, and

Fig. 3 is a plan view of the inner side of the garment showing the same in a flat position.

In carrying out the invention, as will be seen by reference to the drawings, the garment includes a front member, a back member, side members, and an abdominal support member which may be placed in different positions in the garment. As illustrated the front member is so constructed as to include a central section 10 and lateral sections 11 and 12. The sections 10 and 11 are connected by a reinforcing strip 13 and suitable lines of stitching while the sections 10 and 12 are

connected in a similar manner by a reinforcing strip 14 and suitable lines of stitching. Associated with the reinforcing strip 13 I may employ stays, as indicated at 15, and in a like manner stays 16 may be placed in pockets provided therefor by the reinforcing strip 14. These stays 15 and 16 preferably extend from the upper edge of the garment appreciable distances downwardly. This front member is preferably made of inelastic material.

The back member 17 is also preferably made of inelastic material, and may be so constructed as to include a plurality of sections connected by suitable reinforcing strips and lines of stitching and with which there may be associated suitable stays, as indicated at 18, 19, 20 and 21, or otherwise. The garment also includes side members 22 and 23, which are made of suitable elastic material. The right hand side member 22 is connected at its forward edge to the rearward edge of the section 12 by a reinforcing strip 24 and suitable lines of stitching. At its rearward edge this side member 22 is connected to the adjacent edge of the back section 17 in a similar manner and in these portions of the garment I may employ suitable stays, as indicated at 25 and 25'. The forward edge of the back member at the left side of the garment is connected to the rearward edge of the side member 23 by a reinforcing strip 26 and suitable lines of stitching. In the upper portion of this reinforcing strip there may be a pocket for the reception of a stay 27.

At the free end of the front member I use a reinforcing strip 28 to which in spaced positions there is secured a series of hooks 29 and at the free edge of the side member 23 there is a reinforcing strip 30 to which is secured a corresponding series of eyes 31, each eye 31 being adapted to be engaged by a hook 29 in securing the garment in position on the body of the wearer. At the upper edge of the garment I prefer to employ a strip of elastic material, as indicated at 32. This extends from one end of the garment to the other and functions to cause the waist line section of the garment to conform to the waist line of the body. Secured to the for-

ward edge of the back member at the right side of the garment I employ an anchor member 33 and similarly in the left-hand side of the garment extending from the back member there is an anchor member 34.

5 The garment also includes an abdominal support. This support, as illustrated, is constructed to include a front member of inelastic material comprising sections 35 and 35', elastic sections 36 and 37, and end sections 38 and 39. The front sections 35 and 35' are connected along a centrally disposed line. The forward edges of the elastic sections 36 and 37 are connected to the rearward edges of the sections 35 and 35'. The 10 rearward edge of the elastic section 36 is connected to the forward edge of the end section 38, and the rearward edge of the elastic section 37 is connected to the forward edge of the end section 39. The end section 38 is provided with a reinforcing strip 40 secured to which is a series of hooks 41, each adapted to engage with an eye 42 secured to the anchor member 33. In a similar manner 15 the end section 39 is provided with a reinforcing strip 43 to which there is secured a series of hooks 44, each of which is adapted to engage with an eye 45 secured to the anchor member 34. The hooks of the abdominal support member and the eyes connected to the anchor members are spaced like distances apart and the anchor members are longer than the height of the abdominal support member and there are more eyes in the 20 series thereof connected to the anchor members than there are hooks in the series at the edges of the abdominal support member. Consequently the position of the abdominal support member may be raised and lowered 25 depending upon the length of the abdomen of the wearer.

The abdominal support member also includes a reinforcing member 46 which is secured in the lower central portion thereof together with tension straps 47 and 48. The 30 tension strap 47 at its forward end is connected to the edge of the reinforcing member 46 by a suitable line of stitching 49 and extends upwardly to the end member 38. Similarly the forward end of the tension strap 48 is secured to the opposite edge of the reinforcing member 46 by the line of stitching 51 and at its opposite edge to the end member 39 by a line of stitching 52. These 35 straps 47 and 48 therefore incline upwardly and extend over the lower portions of the front sections 35 and 35' and the elastic sections 36 and 37. By this structure, as will be understood, a circumferential tension is afforded by the elastic sections 36 and 37 and an upwardly extending tension in addition to the circumferential tension by means of the tension straps 47 and 48, thereby providing an abdominal support for the abdomen.

65 Also, as indicated, the garment may be

fitted with suitable hose supporters. Those in the front are designated at 54 and 55, those at the sides are indicated at 56 and 57 and those at the back at 58 and 59.

I claim as my invention:

1. In an apparel garment of the type described, an abdominal support member comprising a central inelastic section adapted to extend over the abdomen of the wearer, a reinforcing member secured to the lower central portion of the said central inelastic section and terminating appreciably above the lower edge thereof, an elastic section secured to each of the distant edges of the said inelastic central section, an inelastic end section secured to the distant edge of each of the said elastic sections, the said elastic sections and inelastic end sections extending from the upper to the lower edges of the said abdominal support member, elastic tension straps having the forward ends thereof secured in the said reinforcing member, extending upwardly over the said elastic sections and having their distant ends secured in the said inelastic end members whereby a circumferential tension is exerted by the said elastic members throughout the entire abdominal support member and an upwardly extending tension is exerted in the lower portion of the said abdominal support member which supplements the circumferential tension in this portion thereof, the said tensional forces acting substantially at right angles to one another, and means for detachably connecting the said abdominal support member in different positions to vary the height of the same in the garment.

2. In an apparel garment of the type described, an abdominal support member comprising an inelastic central section, a reinforcing pad having upwardly converging edges secured to the lower front portion of the inelastic central section and terminating appreciably above the lower edge thereof, elastic sections having their forward edges connected to the distant edges of the said inelastic section, inelastic end sections connected to the distant edges of the said elastic sections, the said end sections and elastic sections extending from the upper to the lower edges of the abdominal support member, tension straps having their forward edges secured to the converging edges of the said reinforcing pad, extending over the said elastic sections, and having their distant edges connected to the said inelastic end sections, whereby the said elastic sections exert a substantially uniform circumferential tension from the upper to the lower edges of the abdominal support member and the said tension straps exert an upwardly directed tension in the lower portion of the abdominal support member which supplements the circumferential tension in the lower portion of the abdominal support member, the said ten-

sional forces acting substantially at right angles to one another and means for connecting the said inelastic end sections in the garment to vary the height of the said abdominal support member therein.

5 Signed by me this 7th day of January, 1928.

RICHARD M. BINSWANGER.
